2 SHEETS—SHEET 2.

UNITED STATES PATENT OFFICE.

JOSEPH D. BELL, OF ROCKFORD, ILLINOIS.

NAILING APPARATUS.

1,366,050.

Specification of Letters Patent. Patented Jan. 18, 1921.

Application filed July 24, 1919. Serial No. 313,122.

To all whom it may concern:

Be it known that I, JOSEPH D. BELL, a citizen of the United States, residing at Rockford, in the county of Winnebago and 5 State of Illinois, have invented new and useful Improvements in Nailing Apparatus, of which the following is a specification.

The object of the present invention is to provide an improved implement for driving 10 nails in a row or line, which is particularly advantageous for fastening by means of tacks an edge of a piece of fabric to an article to be upholstered, as, for instance, for upholstering davenport.

15 At present, a skilled upholsterer puts a supply of tacks in his mouth and with his tongue turns each tack in succession so that its head is directed outward. He uses a magnetized hammer, and when he places the 20 magnetized part of the hammer against the head of the tack so disposed in his mouth, the tack clings to the hammer in such a manner that it can be driven without further handling. This manner of feeding the tacks 25 to the hammer with the tongue requires long practice, and, consequently, high wages are demanded.

The difficulty of so feeding the tacks is not the only difficulty that a beginner 30 counters. He cannot always drive the tack into the place where it should go, and often drives it far out of the line. From both of these causes, unless skilled labor is used, which is expensive and uncertain, the work 35 of tacking upholstery progresses slowly and a good deal of the work is spoilt.

The object of the present invention is to provide a device which can be operated by a very simple operation of either hand, so 40 that it is not necessary to feed the tacks by the tongue, but they can be fed by hand, and so that, when a tack is placed on the hammer of the device, it is driven in the place intended, in a line with the others 45 and properly spaced, and all driven well in with one stroke, so that an inexperienced worker can make as good time as a skilled worker by the old system.

In the accompanying drawing, Figure 1 50 is a vertical sectional view showing my improved apparatus in use; Figs. 2 and 3 are cross-sectional views on the lines 2—2 and 3—3 respectively of Fig. 5; Fig. 4 is a plan view of the apparatus detached; Fig. 5 is 55 a side view of the apparatus detached, on a

scale larger than in Fig. 1 and in a direction at right angles to that of Fig. 1.

Referring to the drawing, 1 indicates a table, on which is placed an article 2, here shown as a davenport seat, to be upholstered. 60 It is pressed down on said table by means of a longitudinally extending beam 3, here shown only in cross section, which is pressed down by a screw 4 having a wheel 6 for turning it, and screwed through a threaded 65 sleeve or nut 7, which is held against upward movement by a recessed block 8, pressed against the ceiling 10 of the room, or a part depending therefrom.

11 indicates a horizontally extending strip 70 or board secured, as shown at 12, to the legs of the table and against which is supported by brackets 13, one only being here shown, a horizontally extending strip 14, the upper edge of which is formed into a rack 15, 75 (Fig. 5) and which strip 14 carries, at the top of the side next to the table, a metallic strip 16 secured thereto, the upper edge of said strip 16 forming a track.

This track is here shown as straight, this 80 being the form required for driving a straight row of tacks or nails, but it is not necessarily so, and will correspond in form or curvature with the form or curvature of the object into which it is desired to drive 85 the nails or tacks.

Traveling on said track, is an inverted-channel-shaped carrier 17, here shown as formed of two pieces 18 of angle iron, the horizontally extending members of which 90 are riveted together, one beneath the other. Secured to the side of said carrier remote from the table 1 is the top of a depending bar 19, from the lower end of which extends toward the table a yoke 21 in which is pivoted a roller 22, bearing against said strip 14. Riveted to the middle portion of said carrier is the middle of a yoke 23, (Fig. 1) 95 the sides of which extend upwardly from said carrier, and through the ends of said 100 yoke extends a bolt 27. Said bolt 27 also extends through the upper end of an arm 25, formed of two halves, one on each side of a hammer handle 26, the upper ends of said halves being secured to said handle by 105 the bolt 27, and a bolt 24 also passing through the lower end of said handle and through the middle portion of said arm, so that said handle moves rigidly with said arm 25. Through registering holes 28 (Fig. 110

2) in the lower ends of the two halves of the arm 25 extends the inner end of a coiled spring 29, the outer end of which extends through a hole in a bent-up end 31 of a bar 32 secured to the carrier, and extending horizontally and outwardly therefrom.

Pivoted upon said bolt 24 and rocking with the arm 25 and hammer handle 26, its upper end being secured to said arm 25, by 10 the bolt 27, is a lever 34, the lower end of which is pivoted, as shown at 36, to one end of a twisted link 37, the other end of which is pivoted, as shown at 38, to a dog 39. One end of said dog carries a stud 41 which extends through a slot 42 extending longitudinally in said bar 32, while the other end of said dog has a hole 43 in which is contained a sleeve 45, which also depends through a slot 46 extending longitudinally in a guide 15 plate 47, and parallel with the track. One end of the guide plate 47 is riveted to the central portion of the carrier, the guide plate in general extending behind said central portion, which, in proximity to the 20 guide plate, is cut away between the depending sides of the carrier, so that the guide plate extends between said depending portions. The lower end of said sleeve 45 is flanged, as shown at 50, (Fig. 3) to retain 25 the sleeve in the slot 46. Through said sleeve 45 slides vertically a bolt 44 carrying at its upper end a nut 48 and the head of the bolt, which is lowermost, is adapted, in one extreme position of its reciprocating movement with said dog, to impinge against the adjacent end of the central portion of the carrier, and, in the other extreme position of its movement, to impinge against one of the faces of the rack 15.

40 The device is operated in the following manner: The operator, taking hold of the upper portion of the hammer above the upper end of the arm 25, either before, while, or after drawing backward with his right hand said upper portion against the tension of the coiled spring 29, places with his left hand the head of a tack 51 (Fig. 1) against a magnetized portion 49 of the hammer head. The effect of drawing back the upper portion of the hammer is to move its lower portion toward the table, stretching the spring 29, and also to move the lower end of the lever 34 toward the table. It being supposed that the head or lower end of 45 the bolt 44 is abutting against a face of the rack 15, as shown in Fig. 1, the adjacent end of the dog 39 remains at rest, while the dog 39 itself swings about the hole 43 as center, since it is moved toward the table 50 by means of the twisted link 37, moved with

the lower end of the lever 34. The movement, in an arc of a circle about the hole 43 as center, of the other end of the dog and of the stud 41 in the slot 42, causes the bar 32 and the carrier to move on the track 16 in 65 the direction away from that face of the rack which is engaged by the head of the bolt 44. The parts are of such form and magnitude that the distance through which the carrier so moves brings the hammer into 70 the correct position to drive the next tack. The operator then lets go of the hammer and the hammer head then springs forward with uniform velocity, namely, that due to the tension of the coiled spring 29, and drives 75 the tack through the upholstery and into the object to which it is to be attached. The feed is gained by bringing the member 39 from an angular position relative to the slot 46 to practically a parallel position relative to 80 thereto, and while doing so the bolt 44 is pressed tightly against a rack tooth 15, thereby compelling the whole device to move along the rack until the device is moved to such a distance that when the hammer is in 85 its position to rest, the bolt 44 will be in a position to drop behind the next tooth 15 in the rack.

I claim:—

1. The combination of a carrier, a track 90 upon which said carrier can move, a rack extending adjacent to the track, a hammer pivotally supported upon said carrier, a spring for moving said hammer on its pivotal support in one direction, the movement 95 of the hammer in the opposite direction energizing said spring, and a device moved by the movement of the hammer relatively to the carrier and engaging the rack to advance the carrier through a predetermined distance on its track with each complete vibration of the hammer.

2. The combination of a carrier, a track 100 upon which said carrier can move, a rack extending adjacent to the track, a hammer 105 pivotally supported upon said carrier, a spring for moving said hammer on its pivotal support in one direction, the movement of the hammer in the opposite direction energizing said spring, said carrier having longitudinally slotted members respectively parallel with, and at right angles to, the direction of movement of the carrier, a dog, devices at its ends extending into the slots of said members, one of said devices being 110 adapted to engage the successive faces of the rack, a lever rocking with the hammer, and a link connected at one end with said lever and at the other end with said dog.

JOSEPH D. BELL.
